TOOL OPERATING MECHANISM

George H. Leland, Dayton, Ohio, assignor to The Leland Electric Company, Dayton, Ohio, a corporation of Ohio

Application September 9, 1935, Serial No. 39,664

11 Claims. (Cl. 77—3)

This invention relates to a tool operating mechanism and is designed more particularly for facing the end of a bearing or the like.

One object of the invention is to provide a mechanism for so operating a rotatable tool that it will be caused to move gradually across the face of the work on a constantly changing radius.

A further object of the invention is to provide such a mechanism in which the tool will rotate simultaneously about a fixed axis and about a second axis which is movable transversely to vary the radius on which the tool rotates.

A further object of the invention is to provide such a mechanism in which the rotation of the tool will be automatically stopped at the end of each complete cycle of operation.

A further object of the invention is to provide such a mechanism which will comprise a small number of parts and in which the several parts will be of such a character that they will not be easily broken or disarranged.

Other objects of the invention will appear as the mechanism is described in detail.

In the accompanying drawings Fig. 1 is a longitudinal sectional view taken centrally through a mechanism embodying my invention and partly broken away; Fig. 2 is a transverse sectional view taken on the line 2—2 of Fig. 1; Fig. 3 is a longitudinal section taken centrally through a modified form of the mechanism, partly broken away; Fig. 4 is a front end elevation of the same; Fig. 5 is a section taken on the line 5—5 of Fig. 3 and looking in the direction of the arrows *a*; Fig. 6 is a section taken on the line 5—5 of Fig. 3 and looking in the direction of the arrows *b*; and Fig. 7 is a detail view of a portion of the inner shaft.

In these drawings I have illustrated one embodiment of my invention, together with a minor modification thereof, and have shown the same as designed for facing the end of a motor bearing but it will be understood that these particular embodiments have been chosen for the purpose of illustration only and that the mechanism may take various forms and may be used for various purposes without departing from the spirit of the invention.

In the particular embodiments of the invention here illustrated the work is carried by a work support which is stationary during the operation of the tool. The work illustrated comprises a bearing 5 mounted in the end frame 6 of a motor and this end frame is clamped or otherwise secured to the work support 7. The particular work support shown in Fig. 1 is of that

type which is arranged between two tools and is moved first in one direction to cause one operation to be performed upon the work and is then moved in the other direction to cause another operation to be performed upon the work. Such a work support is well known in the art and need not be illustrated or described in detail. It will be noted that as here shown the work is clamped on that side of the work support opposite or remote from the tool operating mechanism and the work support has a central opening 8 to permit the same to be moved past the tool so that the latter may project beyond the work support and engage the work.

In the construction here illustrated the member which supports the tool is mounted for rotation about a fixed axis coincident with the center of the work which is to be faced and is movable transversely to that axis to move the tool across the work. A second member is rotated simultaneously with the tool supporting member but at a different speed and the two members have cooperating parts controlled by the relative rotation of said members to impart transverse movement to the tool supporting member. Preferably the two members rotate about parallel axes, which may be coincident or spaced one from the other, and the second member has an eccentric part to impart transverse movement to the tool supporting member and thus gradually change the radius of the tool as the latter rotates about said fixed axis.

In the construction shown in Figs. 1 and 2 the mechanism comprises two rotatable members mounted one within the other and simultaneously rotated. The outer or bearing member 9 is journaled in bearings 10 mounted in a tubular main frame 10a and is rotatable about an axis arranged in alinement with the center or axis of the work piece. This bearing member 10 has a longitudinal bore 11 arranged eccentrically with relation to its axis and forming a bearing in which is mounted a tool supporting member 12. In the present construction, both members are of elongate form and may be referred to as shafts and the eccentric bore 11 extends for the full length of the bearing member 9. It will be obvious, however, that the two members may be of any suitable size and shape and may be mounted in any suitable manner. The tool supporting member 12 has at its forward end means, such as a chuck 13, for supporting a tool 14. As here shown, this tool is provided with a cutting edge 15 which is moved across the end of the bearing to face the same

and is also provided with a second cutting edge 16 adapted to engage the inner edge of the bearing face and chamfer the same. The two members 9 and 12 are rotated simultaneously about their respective axes and the tool supporting member will rotate not only about its own axis but also about the axis of the bearing member 9. The two members are rotated at slightly different speeds, the bearing member preferably having the greater speed, and as the bearing member rotates with relation to the tool supporting member the eccentricity of its bore will cause the tool supporting member to be shifted transversely with relation to the axis 15 of the bearing member; thereby gradually and continuously varying the length of the radius of the tool 14 and causing the cutting edge 15 to move slowly across the face of the work 5. At or about the time the cutting edge 15 completes the facing of the work the cutting edge 16 of the tool will engage the inner edge of the work and cut away or chamfer a corner of the bearing 5. When the bearing member has rotated through an arc of 180° with relation to the tool supporting member the axis of the tool supporting member will have traveled in a curved path about the axis of the bearing member from one side of that axis to the other side thereof and the tool will have reached the limit of its transverse movement. The further rotation of the bearing member with relation to the tool supporting member will return the tool to its initial or normal position.

The two members may be rotated simultaneously and a variation of speed may be secured in any suitable manner. In the present instance I have employed a gear drive and have shown a spur gear 17 rigidly secured to the bearing member 9 near that end opposite the tool and meshing with the gear 18 rigidly secured to the shaft 19 of an electric motor 20, a portion only of which is shown. A second gear 21 is mounted on the rear end of the bearing member 9 for rotation with relation thereto and is so connected with the tool supporting member 12 as to cause the latter to rotate therewith but to permit the tool supporting member to have movement transverse to its axis with relation to the gear 21. In the arrangement shown the gear 21 is provided with a stud 22 which extends into a slot 23 in a plate 24 rigidly secured to the end of the tool supporting member 12. This second gear 21 meshes with a second gear 25 rigidly secured to the motor shaft 19. The two gear trains are of different ratio so that the two members will be rotated at different speeds. The gear trains may be of any suitable ratio but the desired difference in speeds is very slight and may be secured by providing the gear 21 with one tooth less than the gear 17 and the gear 25 with one tooth less than the gear 18. For example, by providing the gear 17 with sixty-one teeth and the gear 21 with sixty teeth and providing the gear 18 with fifty-five teeth and the gear 25 with fifty-four teeth the bearing member 9 will be caused to make five hundred and fifty rotations while the tool supporting member 12 makes five hundred and forty-nine rotations. The bearing member will therefore have made one complete rotation with relation to the tool supporting member and the tool will have been moved from its initial position to the limit of its movement and back to its initial position and during this lateral movement it is rotated constantly about the fixed axis of the bearing member 9.

At the end of each cycle of operations as above described the operation of the mechanism is interrupted to permit the finished workpiece to be removed and another workpiece mounted on the work support and I prefer that the interruption 5 of the operation shall be automatic so as to prevent the possibility of the tool again moving over the face of the work. The rotation of the members 9 and 12 may be interrupted in any suitable manner but when, as in the present instance, the 10 mechanism is electrically driven I prefer to interrupt the rotation of the two members by stopping the motor, as by automatically opening a switch which controls the motor. In the present construction the switch is shown as a mercury 15 tube switch 26 which is pivotally mounted in a housing 27 carried by the main frame 10a and has connected therewith an operating handle 28 which extends to the exterior of the housing 27 to enable the switch to be manually moved to 20 its closed position, it being shown in the drawings in its open position. The operating handle 28 extends below the switch and is pivotally connected with the adjacent end of a lever 29 which is pivotally mounted between its ends, preferably 25 on a block of insulating material 30, and extends through an opening 31 into the tubular frame member 10a where it is operatively connected with a device carried by the bearing member 9. In the present construction this device comprises a 30 sleeve 32 slidably mounted on the bearing member 9 but held against rotation with relation thereto and this sleeve is provided with a circumferential groove 33 to receive the end of a lever 29 which is preferably provided with a 35 roller 34. A spring 35 acts on the sleeve 32 to move the same rearwardly, that is, in a direction to move the switch 26 to its open position. The sleeve 32 and the tool supporting member 12 have cooperating parts controlled by the relative 40 movements of the bearing member 9 and the tool supporting member 12 to control the movement of the sleeve by the spring 35. In the construction illustrated a spring pressed plunger 36 is mounted in the sleeve and extends through a slot 37 in the wall of the tubular bearing member 9 into the bore of that member. The tool supporting member is provided with two circumferential grooves 38 and 39 which are connected one to the other by a longitudinal groove 40. The 45 rear circumferential groove 39 is of a greater width than the groove 38 and its forward wall 44 slopes gradually to the edge of the groove 38. The inner end of the yieldable plunger 36 is adapted to enter any one of these grooves. 50 When the mechanism is idle and the parts are in the positions shown the plunger will be seated in the rear groove 39 at one side of but close to the longitudinal groove 40 and when it is desired to start the mechanism into operation the switch handle 28 is moved forwardly to close the switch and at the same time to slide the sleeve 32 forwardly on the member 9 and thus cause the yieldable plunger 36 to ride over the sloping wall of the rear groove and to enter the forward groove 55 38. When seated in the forward groove the plunger will hold the sleeve against rearward movement by the spring 35 until the bearing member 9 has approximately completed one rotation with relation to the tool supporting member 12 and the plunger 36 will then be brought into line with the longitudinal groove 40, thereby releasing the sleeve and permitting the same to be moved rearwardly by the spring 35, which movement will open the switch 36. The opening 60 70 75 80 85 90 95 100

of the switch will not instantly stop the rotation of the two members 9 and 12 but there will be a slight overthrow sufficient to carry the plunger, which has then entered the rear groove 39, out of line with the longitudinal groove 40 so that when the switch is again closed the plunger will be moved over the inclined surface of the rear groove and into the forward groove 38 and will lock the sleeve against rearward movement. If desired, suitable mechanism may be provided to limit the operation of the motor after the switch has been opened but such devices are well known in the motor art and it is not necessary to illustrate or describe the same.

In Figs. 3 to 7 I have illustrated a slightly modified form of the invention in which the mechanism operates in substantially the same manner as above described but in which the construction and operation of the tool supporting member differ somewhat from those above described. In this form of the mechanism a tubular member 44, herein referred to as a shaft, is rotatably mounted in bearings 45 in a tubular supporting frame 46 and rotates about a fixed axis. The longitudinal bore 47 of the shaft is concentric with its axis instead of being eccentric thereto as in the form first described. This bore has portions forming bearings in which an inner member or shaft 48 is rotatably mounted so that it rotates about an axis coincident with the axis of the outer or tubular shaft 44. The two members or shafts are, in the present instance, elongate in form and of substantially equal length. The two shafts may be rotated at different speeds by any suitable mechanism but I prefer to employ for this purpose separate gear trains having different gear ratios and, in the arrangement shown, a gear 49 is secured to the outer shaft 44 and meshes with a gear 50 on the motor shaft 51. A gear 52 is rigidly secured to the end of the inner shaft and meshes with a gear 53 on the motor shaft. The two pairs of gears may have any desired gear ratios, such for example as the ratios described in connection with the first form of the device.

The tool supporting member is separate from and is movable with relation to both the outer shaft and the inner shaft and, in the arrangement shown, it is carried by the outer shaft and is capable of transverse movement with relation thereto. In this construction the tool supporting member comprises a stud 54 having at its outer end means for securing a tool 55 thereto. The stud is provided at its inner end with an enlarged portion or base 56 which overlaps the end of the outer shaft 44, which is preferably enlarged as shown at 57, and has sliding movement on said shaft transverse to the axis of the latter. The tool supporting member may be secured to the shaft in any suitable manner, as by means of a cap 58 screw threaded onto the enlarged end of the shaft 44 and overlapping the base of the tool supporting member. Preferably a spring 59 is confined between the forward face of the base and the flange of the cap to hold the base in firm engagement with the end of the shaft without interfering with its transverse movement with relation thereto. The base is provided on diametrically opposite sides of its center with radial slots or guideways 60 into which extend studs 61 rigidly secured to the forward end of the shaft 44. The stud and slot connection causes the tool supporting member to rotate with the outer shaft 44, about

the axis thereof, but permits the same to move transversely to said shaft.

The base 56 of the tool supporting member is also provided with a slot 62 which preferably extends at right angles to the guideways 60 and this slot 62 receives the forward end of a stud 63 rigidly secured to the forward end of the inner shaft 48 and spaced from the axis thereof. Preferably the stud is provided with a roller 64 which extends into the slot 62 and engages the parallel walls thereof. As the two shafts rotate simultaneously the tool supporting member will be caused to rotate about the common axis of those shafts and as the outer shaft 44 rotates with relation to the inner shaft the position of the tool supporting member with relation to the eccentric stud 63 will gradually change and the stud and slot 62 will cause the tool supporting member to move transversely to its axis, thereby moving the tool 55 across the face of the work. In this form of the apparatus the tool supporting member moves in a straight diametrical line across the axis of the outer shaft while in the form first described the axis of the tool supporting member moves transversely to the axis of the outer shaft in a circular path so that the two axes are at all times spaced a uniform distance one from the other, but in each instance the rotation of the outer shaft through an arc of 180° with relation to the inner shaft will move the tool through its full movement transverse to the axis of the outer shaft and the continued rotation of the outer shaft with relation to the inner shaft will return the tool to its initial or normal position with relation to that axis. It will be obvious that either the inner shaft or the outer shaft may be rotated at the higher speed but inasmuch as the outer shaft is in the present instance the driving shaft I prefer to rotate the outer shaft at the higher speed.

The eccentric stud 63 is preferably adjustable radially to vary the amount of movement imparted thereby to the tool supporting member and, in the present construction, the stud 63 is mounted in a block 65 which is slidably mounted in a transverse bore 66 in the inner shaft 48 and which may be secured in its adjusted position in said bore in any suitable manner, as by the screw threaded stud 63. The forward wall of the bore 66 is slotted, as shown at 68, to permit the adjustment of the stud therein.

This form of the apparatus is also provided with means controlled by the relative rotation of the two shafts for interrupting the rotation thereof, this means being substantially identical with that above described and comprising a tiltable motor switch 69 which is connected by a lever 70 with a member 71 slidably mounted on the shaft 44 for movement lengthwise thereof by a spring 72. The slidable member 71 and the inner shaft having cooperating parts to control the movement of the member 71 with relation to the shaft 44.

While I have shown and described one embodiment of my invention, and one modification thereof, I wish it to be understood that I do not desire to be limited to the details thereof as various modifications may occur to a person skilled in the art.

Having now fully described my invention, what I claim as new and desire to secure by Letters Patent, is:

1. In a tool operating mechanism, a tool, means including driving mechanism for rotating said

- tool about a fixed axis, means separately operated by said driving mechanism for gradually and continuously changing the radius of said tool to cause the same to move over the work 5. transversely to the axis of rotation of the tool, and means controlled in accordance with the transverse movement of said tool to interrupt the rotation of the latter when it has completed a predetermined radial movement.
10. 2. In a tool operating mechanism, a rotatable tool supporting member, a second member rotatable about an axis parallel with the axis of said tool supporting member, means for simultaneously rotating said members at different speeds, said members having cooperating parts controlled by the relative rotation of said members to cause said tool supporting member to move in a direction transverse to its axis, a device connected with one of said members for 20. rotation therewith and for movement with relation thereto, said device and the other of said members having cooperating parts controlled by the relative rotation of said members to control the movement of said device with relation to the 25. member with which it is connected, and means controlled by the movement of said device with relation to the member with which it is connected to interrupt the rotation of said members.
3. In a tool operating mechanism, two rotatable members mounted one within the other, means 30 for connecting a tool with one of said members for rotation thereby, means for simultaneously rotating said members at different speeds, said members having means controlled by the relative rotation of said members to move said tool in a direction transverse to its axis, a device mounted on the outer member for rotation therewith and for movement lengthwise thereof, means for imparting longitudinal movement to said device, the 35. inner member having a circumferential groove and a longitudinal groove communicating with said circumferential groove, said device having a part adapted to extend into said circumferential groove to hold said device against longitudinal movement and to be brought into line with said longitudinal groove by the relative rotation of 40. said members to release said device for longitudinal movement, and means actuated by the longitudinal movement of said device to interrupt 45. the rotation of said members.
4. In a tool operating mechanism, two rotatable members mounted one within the other, means for connecting a tool with one of said members for rotation thereby, and means for simultaneously rotating said members at different speeds, said members having means controlled by the relative rotation of said members to move said tool in a direction transverse to its axis, a device 50. mounted on the outer member for rotation therewith and for movement lengthwise thereof, means for imparting longitudinal movement to said device, the inner member having two circumferential grooves and a longitudinal groove connecting said circumferential grooves, a yieldable plunger carried by said device and adapted to extend into one of said circumferential grooves while said members rotate and to be moved through said longitudinal groove into the other circumferential groove when one of said members 55. has completed a predetermined movement with relation to the other member, means controlled by the longitudinal movement of said device to interrupt the rotation of said members, the last mentioned circumferential groove having an inclined surface leading to the first men-

tioned circumferential groove, and means for moving said plunger over said inclined surface and into said first mentioned groove.

5. In a tool operating mechanism, a support, a member mounted for rotation about a fixed axis 5. on said support and having a bearing eccentric to said axis, a tool supporting member mounted in said eccentric bearing, means for simultaneously rotating said members at slightly different speeds to cause said tool supporting member to 10. be moved transversely with relation to the axis of said bearing member, and means for automatically interrupting the rotation of said members when the member having the higher speed has completed a predetermined movement with 15. relation to the other member.

6. In a tool operating mechanism, a tubular shaft, a second shaft rotatably mounted in said tubular shaft, a tool supporting member mounted on one end of said tubular shaft for rotation 20. therewith and for transverse movement with relation thereto, said tool supporting member having an opening therein, a stud carried by said second shaft, spaced from the axis thereof and extending into said opening, means for radially adjusting said stud with relation to said second shaft, and means for simultaneously rotating said shafts at different speeds.

7. In a tool operating mechanism, a tubular shaft, a second shaft rotatably mounted in said 30. tubular shaft, means for simultaneously rotating said shafts at different speeds, a tool supporting member mounted on one end of said tubular shaft for movement transverse thereto and having radial guideways and a slot transverse to said 35. guideways, studs carried by said tubular shaft and extending into the respective guideways, and an eccentric stud carried by said second shaft and extending into said transverse slot.

8. In a tool operating mechanism, a tubular 40. shaft, a second shaft rotatably mounted in said tubular shaft, means for simultaneously rotating said shafts at different speeds, a tool supporting member having a base, means for supporting said base in sliding engagement with one end of 45. said tubular shaft, said base having radial guideways on opposite sides of its axis and having a slot transverse to said guideways, studs projecting from said tubular shaft into the guideways in said base, a stud mounted on said second shaft, 50. spaced from the axis thereof and extending into the slot in the base, and a spring to hold said base in engagement with the end of said tubular shaft.

9. In a tool operating mechanism, a support- 55. ing structure, two members rotatably mounted on said structure, driving mechanism separately connected with the respective members to simultaneously and continuously rotate the same at different speeds, a tool supporting member mounted on one of the first mentioned members for rotation therewith and for movement transversely thereto, the other of said first mentioned members having an eccentric part to engage said tool supporting member and impart transverse move- 60. ment thereto.

10. In a tool operating mechanism, a supporting structure, a tubular shaft rotatably mounted on said structure, a second shaft rotatably mounted in said tubular shaft, a tool supporting member mounted on one end of said tubular shaft for rotation therewith and for transverse movement with relation thereto, said tool supporting member having an opening therein, a stud carried by 70. said second shaft, spaced from the axis thereof 75.

and extending into said opening, and driving mechanism separately connected with said shafts for simultaneously and continuously rotating the same at different speeds.

- 5 11. In a tool operating mechanism, a rotatable outer member having an internal bearing, an inner member mounted in said bearing, means for continuously rotating said members at different speeds, and means for connecting a tool with one

of said members for rotation therewith and for movement in a direction transverse to the axis of the other member, said other member having a part eccentric to the axis thereof and arranged to act on said tool to impart transverse reciprocatory movement to said tool while it rotates in one direction.

5
GEORGE H. LELAND.
